(57) CLAIM

The ornamental design for a ceiling panel for an airplane, as shown and described.

DESCRIPTION

FIG. 1 is a perspective view of a ceiling panel for an airplane;

FIG. 2 is a plan view of the ceiling panel for an airplane; and, FIG. 3 is a plan view of an alternate embodiment thereof, wherein the only difference from the original embodiment is the two edge corners.

There is no claim to the other views of the ceiling panels. The portions of the airplane shown in broken lines are only part of the environment and are not part of the claimed invention.
